US00D806723S

(12) **United States Design Patent** (10) Patent No.: **US D806,723 S**
Gussev et al. (45) Date of Patent: **** Jan. 2, 2018**

(54) **COMPUTER DISPLAY WITH GRAPHICAL USER INTERFACE**

(71) Applicant: **Axinom Holding OÜ**, Tartu (EE)

(72) Inventors: **Sergei Gussev**, Fuerth (DE); **Ralph Wagner**, Fuerth (DE)

(73) Assignee: **AXINOM HOLDING OÜ**, Tartu (EE)

(**) Term: **15 Years**

(21) Appl. No.: **29/606,095**

(22) Filed: **Jun. 1, 2017**

Related U.S. Application Data

(62) Division of application No. 29/547,827, filed on Dec. 8, 2015, now Pat. No. Des. 791,792.

(51) **LOC (11) Cl.** **14-04**

(52) **U.S. Cl.**

USPC **D14/485**

(58) **Field of Classification Search**

USPC **D14/485-495**

CPC .. G06F 3/048; G06F 3/04842; G06F 3/04847;

G06F 3/0481; G06F 17/211; G06F

17/212

Primary Examiner — Darlington Ly

Assistant Examiner — Daniel J Domino

(74) **Attorney, Agent, or Firm** — Baker & Hostetler LLP

(57) **CLAIM**

The ornamental design for a computer display with graphical user interface, as shown and described.

DESCRIPTION

The FIGURE is a front view of the computer display with a graphical user interface of our design.

The broken lines showing a computer display, text, symbols, and elements of the graphical user interface illustrate portions of the article and form no part of the claimed design.

1 Claim, 1 Drawing Sheet
